CLAIM

The ornamental design for a battery pack for a vacuum cleaner as shown and described.

DESCRIPTION

FIG. 1 is a perspective view of a battery pack for a vacuum cleaner showing our new design.

FIG. 2 is a front view thereof.

FIG. 3 is a rear view thereof.

FIG. 4 is a left side view thereof.

FIG. 5 is a right side view thereof.

FIG. 6 is a top view thereof, shown in enlarged scale; and,

FIG. 7 is a bottom view thereof, shown in enlarged scale. The broken lines show portions of the design that form no part of the claimed design.

1 Claim, 7 Drawing Sheets
